UNITED STATES PATENT OFFICE.

CHARLES M. STROUD, OF MINNEAPOLIS, MINNESOTA, ASSIGNOR OF ONE-HALF TO
SANFORD H. ASHLEY, OF GRAND FORKS, NORTH DAKOTA.

EXPLOSIVE-ENGINE.

1,149,867.

Specification of Letters Patent.

Patented Aug. 10, 1915.

Application filed March 9, 1912. Serial No. 682,687.

To all whom it may concern:

Be it known that I, CHARLES M. STROUD, a citizen of the United States, residing at Minneapolis, in the county of Hennepin and State of Minnesota, have invented certain new and useful Improvements in Explosive-Engines; and I do hereby declare the following to be a full, clear, and exact description of the invention, such as will enable others skilled in the art to which it appertains to make and use the same.

My invention relates to explosive or internal combustion engines, and has for its object to simplify the construction and improve the action thereof.

Generally stated, the invention consists of the novel devices and combinations of devices hereinafter described and defined in the claims.

In the development of the commercial explosive engine, especially those designed for high speeds, it has been found that high efficiency demands an extremely large exhaust port for the escape of spent gases. Attempted provisions for this action have been made chiefly in two different ways, to-wit, by increasing the size of the exhaust port and exhaust valve, and by the use of complicated and expensive arrangements of telescoped cylinders and means for reciprocating one or several of the said cylinders. Attempted improvements along the first noted line have found a serious obstacle, in the fact that when valves of the puppet type, usually employed, are made large and, consequently, relatively heavy, they will be rapidly pounded to pieces, and frequently broken when the engine is run at high speed. The second scheme, as already indicated, requires a large number of parts that are expensive to construct and apply, are subject to much wear, are likely to get out of order and have the general objections resulting from complication of mechanism.

My invention accomplishes the desirable objects above noted by a novel, extremely simple and inexpensive arrangement of a rotary controlling valve, the preferred construction and arrangement of which will be hereinafter described in detail.

My improved arrangement of the rotary controlling valve is capable of use in connection either with two cycle or four cycle explosive or internal combustion engines, but has certain features which are especially

adapted for use in connection with engines of the latter noted type.

In the accompanying drawings which illustrate the invention incorporated in an explosive engine of the four-cycle type, like characters indicate like parts throughout the several views.

Referring to the drawings, Figure 1 is a vertical section taken centrally through the cylinder, piston crank shaft casing and controlling valve of the four-cycle engine, showing the position of the piston and valve just after it has started its intake or suction stroke; Fig. 2 is a horizontal section taken on the irregular line $x^2 x^2$ on Fig. 1; Fig. 3 is a view corresponding in line of its section to Fig. 1, but with some parts removed and shows the position of the piston just after it has commenced its compression stroke; Fig. 4 is a horizontal section taken on the irregular line $x^4 x^4$ on Fig. 3; Fig. 5 is a view corresponding to Fig. 3, but showing the position of the piston just after it has commenced its working or explosion stroke; Fig. 6 is a horizontal section taken on the irregular line $x^6 x^6$ on Fig. 5; Fig. 7 is a view corresponding to Figs. 3 and 5, showing the position of the piston just after it has commenced its exhaust stroke; Fig. 8 is a horizontal section taken on the irregular line $x^8 x^8$ on Fig. 7, showing also the base and certain other parts of the engine; Fig. 9 is a detail view in elevation showing the rotary controlling valve removed from working position; and Fig. 10 is a horizontal section taken on the line $x^{10} x^{10}$ on Fig. 9, some parts being shown in full.

The engine cylinder 1 is shown as supported on a crank shaft casing 2 of suitable construction. Extended longitudinally of the cylinder 1 with its axis parallel to the axis thereof and closely adjacent to one wall of said cylinder, is a cylindrical valve seat casing 3, preferably, and as shown, formed in a part cast integral with the said cylinder. The said valve seat casing 3, at its lower end, opens into the crank shaft casing 2. The wall 4, between the cylinder and the valve seat casing may be very thin, so that the said cylinder and valve seat are brought very closely together, and in the said wall 4, is a long port 5 that extends longitudinally of the cylinder and is approximately coextensive with the movement of the upper or inner face of the piston. For a reason

which will hereinafter appear, this port 5 is provided near its lower or outer extremity with a transverse bridge 6. The piston 7 is connected, by the usual crank rod 8, to a suitable crank shaft 9 journaled in bearings on the sides of the crank shaft casing 2. Outside of the casing 2 the crank shaft 9 is provided with a sprocket 10. Journaled in an extended portion of the casing 2 and projecting therefrom is a counter shaft 11 provided at its outer end with a sprocket 12, over which and the sprocket 10 runs a sprocket chain 13. The sprocket 12 is twice the diameter of the sprocket 10, so that the counter shaft 11 will be given one rotation for each two rotations of the crank shaft. Rotatively mounted in the valve casing 3 is the controller valve, the construction of which will be presently described. This controller valve is, as shown, provided with a depending shaft 14 journaled at its lower end in a bearing located within the crank shaft casing 2. The counter shaft 11 and valve stem 14 are provided with intermeshing gears 15 and 16, respectively. Preferably, the gear 16 is seated on a thrust resisting ball bearing 17.

The outer wall of the valve casing 3 is formed with an admission port 18 and an exhaust port 19, spaced apart vertically, and both located 180 degrees from, or diametrically opposite to the long cylinder port 5. The admission port 18 is offset from the upper portion of the cylinder port 5, in a direction longitudinally of the valve seat.

The rotary controlling valve, for a highly important reason, is made up of a cylindrical body portion 20 and a longitudinally split expandible shell 21. This expandible shell 21 is preferably approximately the same length as the body 20, or at any rate, is made long enough to cover all of the ports 5, 18 and 19, and it is made much like a cylinder packing ring and has an expanding spring action which causes the same to closely fit the cylindrical wall of the valve seat 3 and maintain a tight joint therewith. Said expandible shell 21 may be caused to rotate with and act as a part of the controlling valve, by means of dowel pins 22 applied, as shown, in Fig. 10. The lower end of the body of the valve 20 is rigidly secured to the upper end of the valve stem 14. This controlling valve is provided with an approximately diametrical admission port 23 that extends obliquely through the body and expandible shell of the said valve, so that its opposite extremities lie in different longitudinal zones of the said valve. Otherwise stated, the upper extremity of the said port 23 is at such altitude that it will cooperate only with the upper extremity of the long cylinder port 5, but will never aline with the admission port 18; and, on the other hand, the lower extremity of the said

port 23 is so located that it will aline with the said admission port 18, once in each complete rotation of the said valve and, consequently, once for each two complete rotations of the engine crank shaft. The said controlling valve is further provided with an exhaust port 24, that extends diametrically through the body and spring expandible shell of the said valve and one extremity of which is so located that it will aline with the exhaust port 19, while the other extremity of said port 24 is elongated vertically or longitudinally of said valve and is so constructed and located that it will aline with the long cylinder port 5 once for each rotation of the said controlling valve and, consequently, once for each two rotations of the engine crank shaft. The said admission and exhaust ports 23 and 24 lie in vertical planes that intersect the axis of the said controlling valve at an angle of 90 degrees.

In the upper end of the valve seat casing 3 is an air passage 25 which coöperates with a longitudinal air passage 26 in the body 20 of the controlling valve, to afford "a breather" port or passage for the air drawn into and out of the crank shaft casing under movements of the piston. The air passage 26 takes a tortuous or winding course longitudinally through said valve body 20 and clears or avoids communication with the admission and exhaust ports 23 and 24.

Operation: The operation of the engine described, is substantially as follows: Referring first to Figs. 1 and 2 which illustrate the intake or suction movement of the piston, it will be noted that the crank shaft has moved approximately 45 degrees past its inner dead center, which has carried the piston downward far enough to open the upper extremity of the long cylinder port 5. At this time, the controller valve rotating in the direction indicated in Fig. 2, has already moved the valve admission port 23 into communication with the admission port 18 and with the upper extremity of the cylinder port 5 so that the piston has commenced to draw in the explosive mixture. This communication between the said ports 18, 23 and 5, will be maintained throughout the continued downward or outward intake movement of the piston, and during approximately the first 90 degrees of the rotary movement of the controller valve. During the intake movement of the piston, the exhaust port 24 is, as it will be noted, kept closed by the walls of the valve seat 3. Next referring to Figs. 3 and 4, it will be noted that the piston has been given an initial compression movement and has closed that portion of the long cylinder port 5 which is below the bridge 6, thereby closing communication between the cylinder and the valve exhaust port 24. Here, it will be noted that the bridge 6 is important because other-

wise, in the arrangement shown, the cylinder would be open to exhaust while the piston is making its compression stroke. During the continued compression movement of the piston, both the admission and exhaust ports of the controlling valve remain closed. When the piston reaches the limit of its compression stroke, it overlaps slightly with the upper or inner extremity of the cylinder port 5 and closes the said port 5 at a time when the said port 5 is also closed by the controlling valve. This is important because it affords a double seal against the escape of gases from the explosion chamber 15 of the cylinder, at the instant of explosion, at which instant, the internal compression is at a maximum. Figs. 5 and 6 illustrate positions of the piston and controller valve after the piston has been given a slight or 20 initial part of its working or explosion propelled stroke. During the entire downward or working movement of the piston, both the admission and exhaust ports of the controller valve remain closed, because the exhaust valve 24 remains closed at both extremities by the walls of the valve seat 3 and the upper extremity of the admission port 23 being longitudinally offset from the admission port 18, is also closed by the wall 25 of the valve seat casing 3. Here will be noted the reason for longitudinally offsetting the opposite extremities of the said admission port 23, for otherwise, the cylinder will be open to admission of the explosive 30 vapor during the working stroke. Figs. 7 and 8 indicate positions of the piston and the controller valve when said piston had been given a slight or initial part of its exhaust or scavenging movement. Here it will be noted that when the piston is ready to begin its exhaust or scavenging movement, or slightly before, or slightly afterward, the cylinder for the full working length of the piston movement, is instantly open 35 to exhaust, because the elongated extremity of the valve exhaust port 24 is then in communication with the long cylinder port 5, from end to end thereof. This is of the very greatest importance, because it affords a quick escape for the hot compressed 40 gases and allows the same to escape from the cylinder instantly. Furthermore, this quick escape of the gases from the cylinder takes place from the lower 45 as well as from the upper portion of the cylinder and does not cause the gases to pass upward from the piston, and thence outward through a port in the upper portion of the cylinder, as has hitherto been necessary. Thus, the gases by their instant 50 and free escape from the cylinder are quickly reduced to atmospheric pressure, and hence, produce a very slight, if any, back pressure on the piston and have a 55 minimum heating effect during the exhaust. 60

This feature of opening the cylinder to exhaust through a port extended approximately the full length of the movement of the piston, I believe, to be broadly new and desire to claim the same from the broadest 65 possible point of view. 70

The long cylinder port 5 may, if desired, be subdivided by additional bridges extended both transversely and longitudinally thereof, and in fact, in practice, I propose to 75 do this simply for the purpose of giving a better bearing for the packing rings of the piston. Also, as is evident, the long extremity of the valve exhaust port 24 might be divided, if desired, but, in effect, the 80 said ports, even when thus divided, would constitute long ports and would be within the meaning of the term "long ports", or "extended ports", or "ports extended approximately the length of the piston stroke", 85 as used in this specification and in the claims. 90

Under movements of the piston, the air drawn into and out of the crank shaft casing, is passed inward and outward through 90 the "breather" passages or ports 25 and 26 in the valve seat and controller valve, respectively, and the effect of this is to keep the said valve comparatively cool. This feature of utilizing a passage through a controller valve of the explosive engine as a breather port, I also believe to be broadly new and desire to claim the same broadly. 95

By far the best results are obtained by extending the cylinder port approximately the 100 full length of the piston movement, but a very highly important feature is involved simply in the fact that this cylinder port is extended from a point inward nearly as far as the point reached by the inner end of the 105 piston in its extreme inward movement, outward to a point reached by the inner end of the piston in its extreme outward movement. This provides an arrangement in 110 which the burned products of combustion adjacent to the inner end of the piston may flow directly outward through the cylinder port as soon as the said port is open to exhaust. 115

What I claim is:

1. In an internal combustion engine, the combination with a cylinder and a cylindrical valve seat located entirely outside of the said cylinder with its axis parallel to the axis of the said cylinder, said cylinder 120 having an exhaust port opening into said valve seat and extending substantially the distance of the piston travel, and a rotary valve working in said valve seat and having a port extending approximately the same 125 distance as the port between said cylinder and valve seat. 130

2. In an internal combustion engine, the combination with a cylinder and a cylindrical valve seat located entirely outside of the 130

said cylinder with its axis parallel to the axis of the said cylinder, said cylinder having an exhaust port opening into said valve seat and extending substantially the distance of the piston travel, a rotary valve working in said valve seat and having a port extending approximately the same distance as the port between said cylinder and valve seat, the said valve having also an admission port that is independent of its exhaust port; and the said valve seat having admission and exhaust ports coöperating, respectively, with the admission and exhaust ports of said valve.

15 3. The combination with the cylinder and piston of an explosive engine of the four-

cycle type, the said engine having a crank shaft casing, of a rotary controlling valve having ports coöperating with the port in said cylinder to control admission and exhaust, and the said valve having a longitudinally extended "breather" port or passage connected to said crank shaft casing and through which air will be forced inward and outward to and from said casing. 20 25

In testimony whereof I affix my signature in presence of two witnesses.
